FLETCHER D. GRUND, OF WESTON, AND HOLDEN W. RIGHTMYER, OF TOLEDO, OHIO, ASSIGNEES TO THE AMERICAN SWISS COMPANY, OF TOLEDO, OHIO, A CORPORATION OF OHIO

REMOTE CONTROL FOR DOOR LATCHES

Application filed August 23, 1929. Serial No. 388,003;

This invention relates to vehicle door latches, but more particularly to control means for door latches of the remote control type in which the operating mechanism on the inside of the door is spaced a substantial distance from the latch unit.

An object of this invention is to provide an efficient control member which in its normal latchbolt-retracting operation can be moved throughout its range with substantial-
ly no resistance, but when moved in a non-
bolt-retracting direction encounters resis-
tance until a predetermined point is reached
at which the control member is held in its ad-
justed position, a slightly greater force be-
ing required to move the member from this
position. This arrangement is particularly
useful in connection with a latch unit such
as shown and described in the co-pending ap-
plication of Fletcher D. Grund, Serial No.
388,004, filed August 23, 1929, in which the
outside bolt-retracting handle is rendered in-
operative by a reverse movement of the in-
side operating handle.

The invention is shown by way of illus-
tration in the accompanying drawing, in
which the figure is a side elevation of the con-
trol unit.

The illustrated embodiment of the invention comprises a control unit for the inside of the door which is operable to retract a latch bolt mounted in spaced relation thereto. The unit consists of a mounting plate 1 to which a bearing plate 2 is secured in spaced relation thereto. Disposed intermediate the plates 1 and 2 is a control lever 3 having the usual shaft 4 on which an operating handle (not shown) is connected. Pivoted to the outer end of the lever 3 is a strap 5 extending to the latch bolt and serving to retract the bolt when the lever 3 is moved in a counter-clockwise direction.

Formed on the edge of the lever 3 is a uniformly curved surface 6 which terminates at one end in a raised portion 7. Extending from the raised portion 7 in the opposite direction is an inclined edge surface 8 which terminates at its opposite end in a notch 9. Extending through the bearing plate 2 and engaging the outer side thereof is a leaf

spring 10 which is looped and has a bent-in portion 11 normally engaging the uniformly curved surface 6 adjacent the raised portion 7.

In the normal bolt-retracting operation of the control member the latter is moved in a counter-clockwise direction so that the uniformly curved surface 6 is moved relative to the spring 10 and during such movement the spring offers practically no resistance to this movement throughout the entire range. When it is desired to move the control lever in a reverse direction, such as for dogging the roll-back of the latch unit, the control lever 3 is moved in a clockwise direction, as shown in the drawing, whereupon the raised portion 7 is forced past the end 11 of the spring and thereafter the inclined surface 8 is moved with respect to the spring until the latter engages the notch 9 and then snaps into position to retain the control member 3 in the desired position.

The control lever is retained in the desired position until the operator moves the handle to retract the bolt, whereupon the spring is forced from the notch 9 and the uniformly curved surface 6 is engaged after which no appreciable resistance is afforded by the spring to the movement of the control lever. The above described construction is of im-
portance in that a spring is provided which constantly bears against the control member, but in the normal bolt-retracting move-
ment offers substantially no resistance to its movement, but is effective for retaining the member in the desired dogging position when the required movement in non-bolt-
retracting direction is effected to move the dog to dogging position after a manner well known in the trade.

Changes in details of construction and ar-
rangement may be effected without departing
from the spirit of the invention as defined in
the appended claim.

What is claimed is:

In a door latch, a control lever, means piv-
otally to mount said lever, a bolt-operating strap connected to said lever, a uniformly
curved edge surface on said lever providing
the normal operating range for the lever

movement, a raised edge portion on said lever forming a terminus for said uniformly curved surface, a notch in the edge of said lever on the opposite side of said raised portion, a spring having a portion normally bearing against said uniformly curved surface adjacent said raised portion, and means to anchor an end portion of said spring.

In testimony whereof we have hereunto
10 signed our names to this specification.

FLETCHER D. GRUND.
HOLDEN W. RIGHTMYER.
